EAR CORN SLITTER

Thomas Cannava, 69 E. Main St., Moorestown, N.J.

Filed Oct. 1, 1963, Ser. No. 76,819

Term of patent 14 years

(Cl. D44—29)

FIG. 1.

FIG. 2.

FIG. 3.

FIG. 4.

FIG. 1 is a top plan view of an ear corn slitter embodying my new design;

FIG. 2 is a side elevational view thereof;

FIG. 3 is a sectional view on line 3—3 of FIG. 2; and FIG. 4 is a sectional view on line 4—4 of FIG. 2.

My design is characterized by the relatively narrow head member having an outwardly arcuate front curvature and an inwardly arcuate rear curvature, in combination with a handle having the specific curvatures and side indentations shown, with a reduced portion between the head member and the handle, all as shown.

I claim:

The ornamental design for an ear corn slitter, substantially as shown and described.
